(57) **CLAIM**

The ornamental design for molded holster with belt attachment, as shown and described.

DESCRIPTION

FIG. 1 is a front, perspective view of a molded holster with belt attachment.

FIG. 2 is a front view of a molded holster with belt attachment.

FIG. 3 is a rear view of a molded holster with belt attachment.

FIG. 4 is a first side view of a molded holster with belt attachment.

FIG. 5 is a second side view of a molded holster with belt attachment.

FIG. 6 is a top view of a molded holster with belt attachment; and,

FIG. 7 is a bottom view of a molded holster with belt attachment.

The broken lines in the drawings depict environmental structure of the molded holster with belt attachment that forms no part of the claimed design.

1 Claim, 5 Drawing Sheets
